UNITED STATES PATENT OFFICE.

JOHN MORRIS LATIMER, OF PHILADELPHIA, PENNSYLVANIA, ASSIGNOR,
BY MESNE ASSIGNMENTS, TO CONSOLIDATED FIRE ALARM COMPANY,
A CORPORATION OF NEW YORK.

ALARM SYSTEM.

No. 802,573.

Specification of Letters Patent.

Patented Oct. 24, 1905.

Application filed September 11, 1902. Serial No. 122,928.

To all whom it may concern:

Be it known that I, JOHN MORRIS LATIMER, a citizen of the United States of America, and a resident of the city of Philadelphia, in the 5 county of Philadelphia and State of Pennsylvania, have invented certain new and useful Improvements in Alarm Systems, of which the following is a specification.

The invention herein shown relates to an 10 alarm system, particularly for fire-alarm purposes, which is suited to a building or group of buildings, and comprises a system of electrical circuits and apparatus. Suitable alarm-starting devices or circuit-closers, which may 15 be either manually or automatically operated—as, for example, open-circuit thermostats which close electrical contacts when subjected to a high temperature—are connected with an alarm-signal mechanism by which the 20 alarm is given, usually by means of a break-wheel in an alarm-circuit which connects the various buildings of subscribers to the system throughout the city either with an office from which the various systems installed throughout 25 the city are supervised or with the fire headquarters of the city.

A signal-box, preferably located in the building to be protected, contains various parts of the signal mechanism and operating-coils. 30 Two leads are run throughout the building from this box to each of the circuit-closers. The circuit-closers are normally open and give the alarm by closing circuit between the leads. An alarm-signal magnet-coil is connected between the leads at the signal-box and forms an alarm-circuit with the leads and circuit-closers. The alarm-signal magnet-coil operates suitable alarm-signal mechanism. Each of the two leads has both ends run to 35 the signal-box and connected to a trouble-signal magnet-coil, thereby forming a closed test-circuit which is electrically independent of the test-circuit formed by the other lead, and also forming duplicate alarm-circuits between each alarm device and the alarm-signal mechanism. Suitable trouble-signal mechanism is provided, which operates when current is cut off from or reduced in either trouble-signal magnet-coil. Batteries are introduced 45 at suitable points for supplying each of the circuits.

One feature of my invention consists in diverging the two alarm-circuits between each

of the circuit-closers and the alarm-signal mechanism.

55

Another feature consists in making metallic connections between the alarm-signal magnet-coil and the battery and the leads and confining these connections within or close to the signal-box where they are not liable to injury, 60 in connection with the continuous test of the leads which form the remainder of the alarm-circuit, with the exception of the circuit-closers.

Another feature of my invention relates to 65 the balancing of the trouble-signal magnet-coils, whereby the trouble-signal mechanism will be operated by either coil upon the failure or increase of current in the circuit of the other coil.

70

Another feature of the invention relates to a test-circuit for the alarm-signal battery.

Another feature of the invention relates to a ground-test for all the circuits of the system.

Another feature of the invention relates to 75 a visual indicator adapted to indicate, whenever a circuit-closer operates, the section of the building in which the operated alarm device is located.

In the accompanying three sheets of drawings, Figure 1 is a diagram of the circuits and apparatus local to a building, omitting the visual indicator and the connections required therefor. Fig. 2 is a plan view showing one of the gear-trains in the signal-box. Fig. 3 85 is a view with the casing broken away, showing one of the thermostats. Fig. 4 is a diagram of the circuits and apparatus local to a building, including the visual indicator. Fig. 5 is a section through a building, showing the 90 relation and connections between the various parts of the system.

Referring first to Fig. 1, there are two main leads $a a'$, between which are connected in parallel relation automatic open-circuit 95 alarm-starting devices or circuit-closers $A A'$ and manually-operable circuit-closers $A' A'$, which are distributed throughout the building, and the coils $b b'$ of an alarm-signal magnet B . A battery of cells $f f'$ is introduced 100 at a convenient point for supplying the circuit formed by these parts. As shown, the battery is introduced midway of the magnet-coils. Each of the leads has a course from a magnet-terminal $o o'$ past all of the circuit-closers. The thermostatic circuit-closers are 105

- placed usually in rows along the ceiling of each room and the course of the leads will be back and forth along the rows, the two leads being parallel. After passing to all the devices in the room the leads pass to an adjoining room or floor, where they take a similar course, and so on until the circuit-closers in all the rooms and floors have been connected. Two rows of thermostatic circuit-closers at 5 the top of the diagram indicate two rows on the ceiling of the top story of the building. One row of the same length below and part of a fourth row indicate two rows on the basement-ceiling. The dotted connections between the rows indicate that the rows may be 10 extended and additional rows and floors included, as may be required. Each lead after passing all the circuit-closers is brought back to the point of starting at a terminal of the magnet-coils, preferably over a course as remote as possible from the course over which it leads away from the terminal. Each lead forms a closed test-circuit which is electrically 15 independent of the circuit formed by the other lead. A trouble-signal magnet-coil c and a trouble-signal battery t is included in the circuit formed by the 20 lead a , and a trouble-signal magnet-coil c' and a trouble-signal battery t' is included in the circuit formed by the 25 lead a' . Upon the operation of any one of the circuit-closers two alarm-circuits are established, both of which supply the alarm-signal magnet-coils. One of these circuits will be from 30 the outer terminal p of the battery-cells f of the alarm-signal battery, through the alarm-signal magnet-coil b , up through the lead a at the left-hand side of the drawing to the ceiling of the top story of the building over a 35 zigzag course, through the successive rooms and stories down to the operated circuit-closer, through this device to lead a' and back over a parallel course with lead a to the alarm-signal magnet-coil b' , through this coil to the 40 outer terminal p' of the battery-cells f' of the alarm-signal battery, thereby completing the circuit. The other alarm-circuit will be from 45 the outer terminal p of the cells f of the alarm-signal battery, as before, through the alarm-signal magnet-coil b , as before, down through 50 the lead a at the left-hand side of the diagram, through the trouble-signal magnet-coil c , through the trouble-signal battery t to the basement-ceiling of the building, over a zigzag 55 course through the successive rooms and floors up to the operated circuit-closer, through the device to lead a' and back over a parallel course with lead a through the trouble-signal battery t' , through the trouble-signal magnet-coil c' , through the alarm-signal magnet-coil b' , as before, to the outer terminal p' of the battery-cells f' of the alarm-signal battery, thereby completing this circuit to the 60 battery. The magnet-coils b and b' are wound in the 65

same direction on the magnet B and are constructed so that current flowing in either of the circuits just traced will circulate around the core of the magnet B in the same direction in both of its coils.

It will be seen that no part of either lead is common to both alarm-circuits, that the two circuits diverge from the alarm device and do not again come into proximity to each other except at the terminals of the alarm-signal magnet-coils. Consequently if a fire should follow an accident by which one or both leads are broken in any part of the building one of the alarm-circuits will be left intact to transmit the alarm.

The second alarm-circuit is supplied by the trouble-signal batteries as well as by the alarm-signal battery, and so far as this circuit is concerned the alarm-signal battery is not necessary, if the trouble-signal batteries are 80 of sufficient strength and there is sufficient resistance in that portion of the leads which form the first alarm-circuit to divert sufficient current from the test circuits to the alarm-signal magnet-coil.

The signal mechanism comprises two spring-actuated gear-trains arranged to give two classes of signals. One of the signals is an alarm-signal which is given by the alarm-signal gear-train F only upon the operation 95 of the armature of the alarm-signal magnet B. The other signal is a trouble-signal, which is given by a trouble-signal gear-train T upon the operation of either the armature of the alarm-signal magnet or the operation of the 100 armature of the trouble-signal magnet C. The trouble-signal magnet is energized by either of the trouble-signal magnet-coils c and c' of the two test-circuits. The trouble-signal batteries and these coils are so connected 105 in the test-circuits that the currents in the two coils c and c' will flow in opposite directions around the magnet. Normally the two coils will neutralize each other and the magnet will not be energized while the two batteries remain of equal strength and neither circuit is broken; but upon the failure of either battery or circuit the coil of the other battery or circuit will energize the trouble-signal magnet C and it will attract its armature. Similarly an increase of current in 110 either lead, by short-circuiting or otherwise, would upset the balance of the magnet C and attract its armature. The alarm-signal gear-train F is actuated by a spring s and operates 115 when its escapement g' is released. It carries a make-and-break wheel g^2 in a general alarm-circuit w , which connects the various buildings of subscribers to the system throughout the city with the alarm headquarters. The gear-train can run, if fully wound, upon 120 the release of the escapement until the stop g^3 , attached to one of the wheels, revolves to the right and strikes against a fixed pin g^4 . The gearing ratio is such that the break- 125

wheel will make three revolutions, and thus repeat the signal three times.

The trouble-signal gear-train T is similar in construction and operates when its escapement d' is released. It carries a break-wheel d^2 , which in practice is usually placed in the same alarm-circuit with the break-wheel of the alarm-signal gear-train. This gear-train T can run upon the release of the escapement 10 until the stop d^3 attached to one of the wheels revolves to the right and strikes against a fixed pin d^4 . The gearing ratio is such that the break-wheel will make one revolution and give the signal once. In practice it is preferable to have both break-wheels give the same alarm-number, the two classes of signals being distinguishable by the fact that the alarm-signal is a repeated signal.

The escapement of the trouble-signal gear-train is held from operating by a lever d , which is not provided with any spring to keep it in place, so that when drawn out of the way of the escapement it will not return and interfere with the full operation of the mechanism. This lever d is retracted from the escapement d' either by the armature of the trouble-signal magnet which is attached to it or by the armature of the alarm-signal magnet which is connected to it through the rod l . The connection between the rod l and the lever d is such that operation of the lever by the armature of the trouble-signal magnet will not disturb the detent g , which is operated by the armature of the alarm-signal magnet.

The escapement of the alarm-signal mechanism is held from operating both by a notched wheel g^5 of the trouble-signal mechanism and by the detent g , which is connected to the armature of the alarm-signal magnet, and this escapement of the alarm-signal mechanism is released only when the trouble-signal mechanism has operated and brought the notch in the wheel opposite a prong of the escapement 45 and the alarm-signal magnet continues to retract the detent g away from another prong of the escapement. This detent g is normally held in engagement with the escapement by a spring or by gravity, and will fall into engagement again if the alarm-signal magnet should become deenergized before the trouble-signal mechanism has fully operated. Operation of the alarm-signal magnet consequently first releases the trouble-signal mechanism 50 and permits this to operate, this mechanism serving for this purpose as a slow-acting locking mechanism for the alarm-signal mechanism. After the locking mechanism has operated the operation of the alarm-signal mechanism may take place; but if in the meantime the alarm-signal magnet should be restored to its normal condition the detent g will be brought into engagement with the escapement g' of the alarm-signal mechanism and its operation will be prevented. This is to prevent

the sending of an alarm-signal upon a brief closure of the alarm-circuit, such as might occur by reason of accidental momentary contact of some metal object with both leads or short-circuiting.

In order to further safeguard the system, the alarm-signal battery is placed under continued test by connecting its terminals through a battery-test magnet-coil H with high resistance. So long as the strength of the battery 70 is maintained and the connections are unbroken this magnet holds up its armature; but upon the battery becoming weak or the connections broken, the battery-test coil will be deenergized and the armature will fall and connect the two terminals h h , thereby establishing a path around the trouble-signal coil c for the current in the test-circuit formed by the lead a . This will disturb the balance between the coils of the trouble-signal magnet 75 and the trouble-signal mechanism will be released and will transmit a trouble-signal.

A ground-test coil K of high resistance is provided to give warning in event of the wires of the system becoming grounded. Should a 80 ground occur in either lead, a current sufficient to operate the magnet will flow through the magnet-coil. Thus if, for example, the lead a should become grounded at any point a circuit will be established from the outer 85 terminal p of the battery-cells f through the alarm-signal magnet-coil b , through the lead a to the grounded point, through the ground to the ground G, through the ground-test coil K to the point of connection q between the battery-cells f and the battery-cells f' , which is the middle point of the alarm-signal battery, 90 thereby completing the circuit. As but half of the alarm-signal-battery current can flow, and but half of the coils of the alarm-signal 95 magnet will be in circuit and the connection through the ground-test magnet is of high resistance the alarm-signal magnet will not be energized sufficiently to operate. The ground-test magnet K will, however, attract its armature and connect the terminals h , thereby establishing a path around the trouble-signal coil c and upset the balance of the magnet C, 100 causing the operation of the trouble-signal mechanism as upon the operation of the battery-test magnet H.

The visual indication and the apparatus and circuits requisite for its operation are illustrated in Fig. 4, which shows diagrammatically these added to the apparatus and circuits heretofore described and shows two rows of circuit-closers for the first story in addition to the rows for the top story and the basement. The circuit-closers on the basement-ceiling form one group, those on the first story form 110 a second group, and those on the top story form the last group. The circuit-closers for intermediate stories will form intermediate groups. A gear-train U, operated by a spring s' , is normally restrained from operating by a 115

notched wheel u , which holds a prong of the escapement u' . When the alarm-signal mechanism F has been started by the operation of a circuit-closer, the notch in the wheel u will 5 be brought opposite the prong of the escapement u' , permitting it to operate in a manner similar to that heretofore described in reference to g' and g^5 , and the gear-train U then drives a make-and-break cylinder u^2 through 10 one revolution, thereby opening and closing successively a series of contacts in one of the leads. It first opens contacts u^3 in one of the leads to prevent new signals from being transmitted from circuit-closers higher up in the 15 building. It also opens contacts v , which form a short circuit across the connections from this lead to the visual indicator V. The connections of this indicator and the connections of the contacts u^3 to the lead are on opposite sides of the connection o' from the 20 alarm-signal-battery current to this lead. The visual indicator is now included in the second alarm-circuit, heretofore traced from the alarm-signal battery, and this will continue 25 from the outer terminal p of the cells f, f' of the alarm-signal battery, through the alarm-signal magnet-coils b , down through the lead a at the left-hand side of the diagram through the trouble-signal magnet-coil c , through the 30 trouble-signal battery t to the basement-ceiling of the building, over a zigzag course through the successive rooms and stories up to the operated circuit-closer, but if more than one is operated to the one on the lowest floor 35 only, through the operated device to lead a' , back over a parallel course with lead a , but through as many of the contacts $v' v^2 v^3$ as are connected with lead a' below the operated circuit-closer, through the trouble-signal battery 40 t' , through the trouble-signal magnet-coil c' , the magnet-coil of the visual indicator V, through the alarm-signal magnet-coil b' , to the outer terminal p' of the battery-cells f, f' of the alarm-signal battery, thereby completing 45 the circuit to the battery. The visual-indicator magnet then attracts its armature and spaces the pointer to the basement indication. Further revolution of the break-cylinder successively opens and closes contacts v' between 50 the basement and first story, contacts v^2 between the first story and the second story, contacts v^3 between the second story and the third story, and so on to the contacts between next to the top story and the top story of the building, the contacts v and u^3 remaining open. At each making and breaking of these contacts in the lead a' below the operated circuit-closer the current through the magnet-coil of the indicator will be interrupted and restored, 55 and the pointer will be spaced one division, and it will stop at the indication of the lowest story on which a circuit-closer has operated at the time when the break-cylinder is revolving. No current flows to the visual-indicator magnet through the leads above the lowest 60

operated circuit-closer after the break-cylinder has started, owing to the opening of the lead a' at contacts u^3 , and the opening of this portion of the lead a' at the break-cylinder will not space the visual indicator.

70

From the foregoing it will be seen that the circuit above traced through the visual-indicator magnet, if the lowest operated thermostat is in the basement, will remain closed throughout the operation of the break-cylinder, and the indicator will be spaced to the basement indication by the current which is diverted through it on the opening of the short circuit around the indicator magnet-coil at the contacts v . If the lowest operated thermostat is in the first story, the contacts v' will be included in the circuit, and these will be opened and closed by the break-cylinder, thereby spacing the indicator an additional indication beyond the basement indication. 80 If the lowest operated thermostat is in the second story, the contacts v' and v^2 will be included in the circuit, and these will be opened and closed in succession by the break-cylinder, thereby spacing the indicator two indications beyond the basement indication. If the lowest operated thermostat is in the third story, the contacts v', v^2 , and v^3 will be included in the circuit, and these contacts will be opened and closed in succession by the break-cylinder, thereby spacing the indicator three indications beyond the basement indication. 90 In like manner additional contacts v^4 and v^5 intervene between the upper stories and afford means for breaking the circuit and spacing the indicator and show the operation of thermostats or other alarm apparatus in these stories.

95

After the break-cylinder has stopped there can be no further opening and closing of the circuit, and the indicator will remain at the indication to which it was spaced by the operation of the break-cylinder, thus affording a permanent indication of the lowest point and origin of the alarm, even though the cause (if fire) may have spread to other parts of the building when the indicator is consulted.

105

Having thus described my invention, what I claim as new, and desire to secure by Letters Patent of the United States, is—

110

1. In an alarm system, the combination of circuit-closers, alarm-signal mechanism operated by the closure of any of the alarm devices, parallel local leads forming two continuous diverging circuits between each of the circuit-closers and the alarm-signal mechanism, means for automatically starting the signal mechanism when either circuit is interrupted and independently of the condition of the other circuit, and a source of electrical energy for said circuits, substantially as described.

115

2. In an alarm system, the combination of leads forming independent test-circuits, circuit-closers connected in parallel relation be-

120

between the leads, an alarm-signal magnet-coil operated by the closure of any of the circuit-closers and connected between the leads and forming an alarm-circuit with the leads and circuit-closers, a source for supplying electrical energy to said circuits, metallic connections only between the source of electrical energy and the other parts of the alarm-circuit, an alarm-signal mechanism operable by the alarm-signal magnet-coil, a trouble-signal magnet-coil in each test-circuit, and trouble-signal mechanism operable by the change of electrical condition of either trouble-signal magnet-coil, substantially as described.

3. In an alarm system, the combination of leads forming independent test-circuits, circuit-closers connected in parallel relation between the leads, an alarm-signal battery, an alarm-signal magnet-coil operated by the closure of any of the circuit-closers and connected between the leads and forming an all-metallic alarm-circuit from the battery with the leads and circuit-closers, an alarm-signal mechanism operated by the alarm-signal magnet-coil, a trouble-signal battery and a trouble-signal magnet-coil in each test-circuit, and trouble-signal mechanism operated by the change of electrical condition of either trouble-signal magnet-coil, substantially as described.

4. In an alarm system, the combination of leads forming independent test-circuits, circuit-closers connected in parallel relation between the leads, an alarm-signal magnet-coil operated by the closure of any of the circuit-closers and connected between the leads and forming an alarm-circuit with the leads and circuit-closers, a source for supplying electrical energy to said circuits, an alarm-signal mechanism operated by the alarm-signal magnet-coil, a trouble-signal magnet-coil in each test-circuit, and trouble-signal mechanism operated by the change of electrical condition of either trouble-signal magnet-coil, substantially as described.

5. In an alarm system, the combination of leads forming independent test-circuits, circuit-closers connected in parallel relation between the leads, an alarm-signal battery, an alarm-signal magnet-coil operated by the closure of any of the circuit-closers and connected between the leads and forming an alarm-circuit with the leads and circuit-closers, an alarm-signal mechanism operated by the alarm-signal magnet-coil, a trouble-signal battery and a trouble-signal magnet-coil in each test-circuit, and trouble-signal mechanism operated by the change of electrical condition of either trouble-signal magnet-coil, substantially as described.

6. In an alarm system, the combination of leads forming independent test-circuits, circuit-closers connected in parallel relation between the leads, an alarm-signal battery, an alarm-signal magnet-coil operated by the closure of any of the circuit-closers, connections

between the alarm-signal battery and the alarm-signal magnet-coil and the leads, an alarm-signal mechanism operated by the alarm-signal battery and the alarm-signal magnet-coil, a battery-test coil in shunt with the alarm-signal battery, a trouble-signal battery and a trouble-signal magnet-coil in each test-circuit, and trouble-signal mechanism operated by the deenergizing of the battery-test coil or either trouble-signal magnet-coil, substantially as described. 70 75

7. In an alarm system, the combination of leads forming independent test-circuits, circuit-closers connected in parallel relation between the leads, an alarm-signal battery, an alarm-signal magnet-coil operated by the closure of any of the circuit-closers, connections between the alarm - signal battery and the alarm-signal magnet-coil and the leads, an alarm - signal mechanism operated by the alarm - signal battery and the alarm - signal magnet-coil, a ground-test coil, connections from the middle point of the alarm-signal battery through the ground - test coil to ground, a trouble-signal battery and a trouble-signal magnet - coil in each test-circuit, and trouble-signal mechanism operated by the energizing of the ground-test coil or the deenergizing of either trouble-signal magnet-coil, substantially as described. 80 85 90 95

8. In an alarm system, the combination of leads forming independent test-circuits, circuit-closers connected in parallel relation between the leads, an alarm-signal battery, an alarm-signal magnet-coil operated by the closure of any of the circuit-closers, connections between the alarm-signal battery and the alarm-signal magnet-coil and the leads, an alarm-signal mechanism operated by the alarm-signal battery and the alarm-signal magnet-coil, a battery-test coil in shunt with the alarm-signal battery, a ground-test coil, connections from the middle point of the alarm-signal battery through the ground-test coil to ground, a trouble-signal battery and a trouble-signal magnet-coil in each test-circuit, and trouble-signal mechanism operated by the energizing of the ground-test coil or the deenergizing of the battery-test coil or either trouble-signal magnet-coil, substantially as described. 115

9. In an alarm system, the combination of circuit-closers, an alarm-signal mechanism, a slow-acting locking mechanism for the alarm-signal mechanism, means operated by the closure of any of the circuit-closers for releasing the locking mechanism and sending a complete preliminary alarm, and automatic means for detaining the alarm-signal mechanism in case of the restoration of the normal condition of the means for releasing the locking mechanism before the completion of the operation of the locking mechanism, substantially as described. 120 125

10. In an alarm system, the combination of leads forming independent test-circuits. cir- 130

cuit-closers connected in parallel relation between the leads, an alarm-signal battery, an alarm-signal magnet-coil operated by the closure of any of the circuit-closers, connections 5 between the alarm-signal battery and the alarm-signal magnet-coil and the leads, an alarm - signal mechanism operated by the alarm-signal battery and the alarm-signal magnet-coil, a trouble-signal battery and a trouble-signal magnet-coil in each test-circuit, trouble - signal mechanism operated by the alarm-signal magnet-coil or by the deenergizing of either trouble-signal magnet-coil, and means operated by the trouble - signal 10 mechanism for preventing the operation of the alarm-signal mechanism until the trouble-signal mechanism has operated, substantially as described.

11. In an alarm system the combination of 20 an alarm-circuit, a plurality of serially-arranged groups of circuit-closers connected to the alarm-circuit, an alarm-signal battery, an alarm - signal magnet-coil, an alarm - signal mechanism operated by the alarm-signal battery and the alarm-signal magnet-coil, a visual 25

group-indicator, means for successively opening the circuit between successive groups of circuit-closers, and means dependent upon the presence of current at the successive points of opening between the groups to determine 30 the amount of advance of the group-indicator, substantially as described.

12. In an alarm apparatus, signal-transmitting mechanism, means for normally restraining the movement thereof, a trouble-signal magnet, means controlled thereby for releasing the restraining means in case of a trouble-alarm only, means for stopping the transmitting mechanism after a complete trouble-alarm signal, an alarm-signal magnet, and 35 means operated thereby adapted to permit the further operation of said transmitting mechanism for sending a series of alarm-signals similar to the trouble-signal.

Signed by me at New York city this 9th day 45 of September, 1902.

JOHN MORRIS LATIMER.
